UNITED STATES PATENT OFFICE.

JAMES A. WATKINS, OF DETROIT, MICHIGAN, ASSIGNOR, BY MESNE ASSIGNMENTS, TO AMERICAN BLOWER CORPORATION, OF DETROIT, MICHIGAN, A CORPORATION OF DELAWARE.

CENTRIFUGAL FAN.

Original application filed December 18, 1920, Serial No. 431,590. Divided and this application filed November 3, 1923. Serial No. 672,526.

This invention relates to improvements in centrifugal fans, and more particularly to the improved type of fan described in my application filed December 18, 1920, Serial No. 5 431,590, Patent No. 1,484,597, in which the fan is provided with an improved annular peripheral discharge nozzle, and the usual scroll volute housing is dispensed with, the present application being a division of said application.

The object of the present invention is to simplify and reduce the cost of construction, and to provide an improved construction of the kind referred to, particularly adapted for 15 use in those instances in which a fan is employed with an engine or in a machine having an enclosing casing and a fly wheel.

Important novel characteristics of the invention reside in the special construction in 20 which the engine or other machine has portions forming the annular peripheral discharge nozzle of the centrifugal fan, and particularly in the special construction and association of parts in which the engine or machine casing has a part constituting part of 25 the peripheral discharge nozzle, and also such a construction in which the fly wheel is utilized to form part of the discharge nozzle, the resulting structure possessing material advantages from the stand point of simplicity and economy in production.

The invention, with other objects and advantages thereof, and the particular construction, combinations and arrangements of parts comprising the same, will be understood from the hereinafter contained detail description when considered in connection with the accompanying drawings, forming part hereof, and illustrating one embodiment of the invention.

In the drawings:

Figure 1 is a part section and side elevation of an internal combustion engine equipped with a centrifugal fan constructed in accordance with the present invention.

Figure 2 is a vertical central section of part of the centrifugal fan structure illustrated Figure 1.

Figure 3 is a side elevation of the structure 50 illustrated Figure 2 with part of the front plate of the fan wheel broken away.

In the drawings the invention is illustrated in connection with one of the standard

types of internal combustion engines. A designates the engine, *a* the engine shaft and *b* the engine casing having an upper section *b'* provided with air inlet openings *b*².

Referring now to the improved centrifugal fan of the present invention, the particular construction shown comprises a flat back ring member or disk 1, a front coned disk 2, and blades 3 located between and suitably secured to the back disk 1 and front coned disk 2. In this instance, the blade structure shown consists of an inner radially extending part 3^a, 65 an intermediate part 3^b curved in approximately a segment of a cylinder, and an outer portion 3^c extending in a direction diverging from the plane of the inner radial portion 3^a, the blades being disposed, as illustrated, with 70 reference to the direction of rotation of the fan wheel indicated by the arrow.

4 designates a fly wheel suitably secured to the engine shaft *a* and having a hub part 4^a, a web part 4^b, and an outer part 4^c. The structure including the back ring member 1 front disk 2 and blades 3, is positioned alongside of the fly wheel 4 with the back disk or ring member 1 fitting there against and firmly secured thereto, the hub part 4^a and adjacent 75 portion of the fly wheel structure constituting the hub and part of the back end wall or plate of the fan wheel. The fly wheel is shown provided at one side with a conoidal surface 4^d, at its hub part, and with an annular depression or recess 4^e, the back disk or ring member 1 being seated in the recess 4^e with its outer face flush with the adjoining portion of the conoidal surface 4^d, the latter forming a continuation of the back ring member 1 and completing the back wall or end plate portion of the fan wheel. 4^f designates an annular recess to accommodate the projecting portions 5 of the blade connections. Any suitable means may be employed to secure the 80 back ring member 1 to the fly wheel 4, that shown in the drawings consisting of screws 6.

The back ring member 1 and the front coned disk 2, as shown, terminate substantially at the tips of the fan blades 3, and the annular 100 peripheral discharge nozzle for the fan is formed by the outer peripheral part 4^c of the fly wheel 4 and an annular extension 7 of the engine casing adjoining an opening 8 in one side thereof, said parts constituting in effect 105 substantial continuations of the end walls or

shrouding of the fan wheel, and having converging wall portions and outer diverging portions, the fly wheel 4 and fan wheel parts 1, 2, 3, rotating together, and the annular extension 7 of the engine casing being fixed, said annular extension 7 extending close along side of the front disk 2 of the fan wheel but sufficiently spaced therefrom to permit free rotation of the front disk 2 relative thereto.

10 The annular extension 7 of the engine casing which is shown conical shaped corresponding to the coned shaped form of the front coned disk 2 of the fan wheel and extending parallel to the latter, is provided with an outer outwardly flaring lip portion 7'. The opposing side face of the outer peripheral portion 4^c of the fly wheel has an inwardly curved portion 9 extending from the outer marginal edge of the back disk 1 and flush with the outer 15 face thereof, from thence a conical portion 10, and an outer outwardly curved lip portion 10'.

The annular peripheral discharge nozzle formed by the annular extension 7 of the engine casing and the outer peripheral portion 4^c of the fly wheel 4 is shaped to conform to the path of the air as it would leave the fan wheel under open discharge conditions, no material change in the direction of 20 the air is effected, the nozzle simply acting to continue the convergence of the air to such a point as to give it sufficient directive velocity, and at this point providing an efficient discharge. In this way the diffusion takes 25 place a considerable distance from the fan wheel, less disturbance being caused at the exit of the blades resulting in increased efficiency.

The special construction and arrangement 30 of parts, hereinbefore described, as will be appreciated, results in considerable saving of material and the cost of production, the structure provided being of a simple, compact and efficient nature.

45 While in the drawings is illustrated a specific embodiment of the invention; it will, of

course be understood that changes and variations in the particular construction shown may be made; instead of the particular type of fan wheel and blade illustrated, the invention may be practiced with the various other types of fan wheels and embodied in other forms as will appeal to those skilled in the art, and falling within the scope of the appended claims, without departing from the 55 spirit of the invention.

What I claim is:

1. The combination with an engine having a casing, of a fan wheel positioned at one side of the fly wheel of the engine, said fly wheel having an outer annular peripheral portion extending beyond the tips of the blades of the fan wheel, and the engine casing having an opening and an annular extension adjoining said opening extending beyond the tips of the fan blades, said outer peripheral portion of the fly wheel and said annular extension of the engine casing forming an annular peripheral discharge nozzle for the fan wheel. 60

2. The combination with an engine having a casing, of a fan wheel, comprising a back ring member, a front disk, and blades between the back ring member and the front disk, the back ring member and front disk terminating 75 substantially at the tips of the blades of the wheel, said fan wheel being positioned adjacent the fly wheel of the engine and secured to the fly wheel, the engine casing having an opening and an annular extension adjoining 80 said opening, said annular extension extending beyond the tips of the blades of the wheel, and said fly wheel having an outer annular peripheral portion extending beyond the tips of the blades, said outer peripheral portion 85 of the fly wheel and said annular extension of the engine casing forming an annular discharge nozzle for the fan wheel.

In testimony whereof I hereunto affix my signature.

JAMES A. WATKINS.
